Oelsner.

UNITED STATES PATENT OFFICE.

KARL GUSTAV OELSNER, OF RIVERTON, WYOMING.

LIFE-SAVING DEVICE.

1,232,713.

Specification of Letters Patent. Patented July 10, 1917.

Application filed November 4, 1916. Serial No. 129,635.

To all whom it may concern:

Be it known that I, KARL GUSTAV OELSNER, a naturalized citizen of the United States, and a resident of Riverton, in the county of Fremont and State of Wyoming, have invented new and useful Improvements in Life-Saving Devices, of which the following is a full, clear, and exact description.

This invention relates to improvements in life-saving devices, boats and rafts generally and especially to the United States Patent No. 1,199,107, patented September 26, 1916, and the objects of my improvement are first to provide the said rafts with sufficient foodstuffs and fresh water and other necessities, second, to provide the rafts with sufficient seats, third, to provide every raft with a protecting device against the waves, 20 to provide every raft with signaling means.

To such end the invention consists essentially in a log raft, carrying an attachment, formed by a plurality of at least three similarly shaped boxes of equal size. The invention further consists in a protection net, fastened to the said attachment; and a signaling means on the attachment.

The invention is illustrated in the accompanying drawings, in which—

Figure 1 shows the protection net expanded. Fig. 2 shows a top or plan view of the attachment after connection of the boxes. (In the drawings two parts only are shown.)

Fig. 3 shows a side view of the said attachment;

Fig. 4 shows the small boxes inside of the big boxes;

Fig. 5 shows the small boards;

Fig. 6 shows the transverse boards;

Fig. 7 shows the composed flagpole.

In order to enable those skilled in the art to make and use my invention, I will now describe the same in detail.

Numeral 16 indicates the protection net, made from ropes and fastened to four sticks 17, made from strong wood with two holes 17^a near the bottom registering with the two holes in the sockets 22.

Numeral 18 indicates the cleats, to position the big boxes.

Numeral 19 indicates the cleats, to position the small boxes.

Numeral 19^a indicates cleats on the top of the middle box, to position the provision box 14.

Numeral 20 indicates the three big boxes, which form the attachment (in the drawings the boxes 20^a and 20^b only are shown). Every box is divided in three similarly shaped parts with covers; every part is divided in three similarly shaped compartments (in the drawings only two parts with two compartments are shown).

Numeral 21 indicates the said covers; they have two hinges, a simple lock and in the middle the said cleats. The corner covers carry cross cleats.

Numeral 22 indicates the sockets on the corners of the attachment, for reception of the four sticks of the protection net.

Numeral 23 indicates the small boxes inside of the big boxes. They are filled with food-stuffs, fresh water bottles, nails, hammer, screws, ropes, and other necessities, as medicaments and carry outside near the bottom two rings.

Numeral 24 indicates the small boards with holes inside the big boxes.

Numeral 25 is the flag pole, composed of three bamboo-sticks. On the top is shown 80 flag and lantern.

The boxes are painted blue, the small boxes with medicaments blue with a red cross.

The boxes 20 have the same height as the logs and boards of the original raft combined, that is to say: if the logs are 12 inches high and the boards 3 inches high, then the boxes will be made 15 inches high. In such a way material for numerous rafts 90 can be arranged on deck as to form a deck attachment.

In case of a shipwreck all this material slips automatically into the water. There the framework is constructed, as described 95 in United States Patent Number 1,199,107, granted to the applicant September 26, 1916.

After that the three boxes are laid over the raft in the position indicated by the cleats on each end of the transverse boards.

Now the small boxes have to be removed from the big boxes and placed on the spots, indicated by the cleats 19 and the cross cleats 19^a. The big boxes have to be connected with the raft by rings and ropes, the small boxes with the big boxes in the same way; the small boxes are connected together by the small boards, which are nailed on their sides.

This done the double walled provision box 110

is laid over the middle box on the spot indicated by the cross cleats and fastened in the same way.

Now the four sticks of the net are fixed 5 into the 4 sockets and screwed firmly. Over the top, ropes are stretched crosswise and lengthwise and the cover laid over these ropes.

The flagpole is fixed into the socket, which 10 is nailed on a corner of the provision box and screwed too. On the top the flag is raised at daytime and the lantern at night time.

The raft completed people sit down on the 15 prepared seats, with the arms linked together.

I am aware that prior to this my invention many rafts were constructed of every

description, without demonstrating clearly the power of united people in a shipwreck, 20 if properly instructed.

Therefore I claim:

A raft attachment comprising a plurality of similarly shaped boxes of equal size and adapted to be connected, sockets at the corners of said boxes, a protection net engaging said boxes, smaller boxes and boards inside of the first named boxes adapted to form seats upon said raft attachment, signaling means and means to connect said raft 25 30 attachment to a raft.

KARL GUSTAV OELSNER.
